CHANGE OF DIRECTION ROLLERS

Robert A. Liebel, Allentown, Pa.

Application January 12, 1946, Serial No. 640,805

4 Claims. (Cl. 74—241)

1

This invention relates to a roller assembly for causing change of direction of flexible sheet material being passed thereover.

The invention is particularly useful in connection with the festooning of coated sheet steel or the like in chambers heated to cause setting of the coating composition. The invention will first be illustrated, therefore, by description in connection with such use.

Flexible strip steel, although rolled or cut to uniform width of strips, cannot be depended upon to have straight edges. Camber is frequently present; the edges of the strip vary in distance from an imaginary straight center or median line.

When such a standard strip is coated and then sent through a festoon chamber of conventional type, between side guide members, suitably flanges on rollers at positions where the sheet undergoes strong flexing and change of direction in the chamber, the strip creeps from side to side, because of the camber or other imperfections. As a result, the edges of the strip must either bend against the guide members or be shifted by the guides back into the desired path of travel. This shifting of the strip is difficult to accomplish. In fact, the sheet either with or without a coating shows such friction on the conventional supporting rollers that the edge of the strip is often bent or deformed by crowding against a guide member without the strip itself being actually shifted as desired. Even when the mechanism is stopped and drawing of the strip through the festoon is no longer in progress, it is still extremely difficult, even by hand manipulation with suitable tools, to shift the strip along the roller in direction generally parallel to the axis of rotation of the rollers without deforming or permanently marking the strip.

The present invention provides a mechanism which causes the shifting of the strip from side to side to be automatic and dependable, without bending the edges of the strip. The invention provides also special means for returning the edges of the strip to the supporting mechanism if, because of unevennesses of width of the strip or for other reasons, the strip temporarily becomes disengaged from the supporting mechanism.

Briefly stated the invention comprises an assembly for effecting change of direction of flexible strip material to be passed continuously thereover, including two supporting rollers with narrow or ribbon like faces, means mounting the rollers in spaced relationship to each other, and guide members controlling the travel of the strip, preferably flanges extending from the outer ends of the rollers.

In a preferred embodiment, the invention includes also a tapered portion or extension of the edge of the face of the roller that is remote from

2

the flange and an idling or inner roller disposed adjacent to the end of the tapering portion and of diameter somewhat greater than the narrow end of the tapering portion but smaller than the diameter of the widest part of the face of the supporting rollers first mentioned.

In a modification, the spaced rollers may be in reality one roller of reduced diameter at positions intermediate the end portions with the narrow or ribbon like faces described above.

I have found that, with the rollers of narrow faces, the strip material being drawn thereover shifts readily from side to side. As a result, an edge which because of camber extends beyond the median line of the strip by more than the average amount is not bent by the flange which the edge strikes. The whole strip shifts easily away from the flange, to relieve the pressure on the flange and keep the strip approximately centered between the two supporting rollers. Also I have found that, with the tapered extension which becomes of smaller diameter in direction away from the face of the roller and with the inner or idling roller of dimensions stated, temporary disengagement of an edge of the strip steel from the face of the roller because of decreased width of the strip is quickly corrected as the strip again shows its full width, the inner roller serving to insure return of the edge of the strip when the strip of normal width contacts the tapered portion and the tapered portion serving as means of returning or mounting the edge of the strip of normal width upon the part of the face of the roller of full width.

In one embodiment the inner roller is formed in separate parts which together total less in width than the normal width between the two supporting rollers. The said parts are adjustable as to positions along the axis of rotation of the whole assembly as are the supporting rollers. As a result the whole assembly may be changed in length to accommodate strips of different widths.

The invention will be further illustrated by description in connection with the attached drawing to which reference is made.

Fig. 1 shows a side view of my assembly partly in section and partly diagrammatic.

Fig. 2 is a sectional view on a somewhat larger scale of one of the change of direction roller assemblies.

Fig. 3 is a fragmentary sectional view of a supporting roller that may be substituted for one of the supporting rollers of Fig. 2.

There is shown a coating bath 10 and means including the winding mechanism 12 for drawing strip steel or like sheet material 14 through the coating bath, under the immersion roller 16, between the coating pair of rollers 18 which remove excess of coating material and smooth the

coating, into the treating chamber 10, over the change of direction roller assemblies 20, 22, 24, 26 and 28, and over the guide roller 30.

The construction of the roller assemblies 20 to 28 inclusive is shown in detail in Fig. 2, showing particularly the features of the representative roller assembly 20. This assembly includes two spaced parts or narrow faced rollers 20. Each roller has a narrow or ribbon-like face 32, a flange guide member 34 extending from the edge of the face that is outward in the assembly and a tapering or frusto-conical extension 36. This tapered portion extends from the edge of the face of full width, that is of full diameter, in direction away from the said flange.

There are shown also in Fig. 2 an inner roller that is suitably in the form of a number of spaced parts 39, 38, and 40.

The various elements described in connection with Fig. 2 are mounted centrally on the shaft 42 so that all the parts have the same axis of rotation. The shaft may be driven by conventional means (not shown) but is ordinarily not driven and serves simply as a means of support permitting rotation.

The several parts of the inner roller are together of overall width less than the distance of spacing apart of the supporting rollers at the two ends of the assembly in Fig. 2. Means such as the set screws 44 are provided for setting the said parts at spaced positions along the shaft 42. Also collar 46 and set screw 48 are provided for limiting the outward movement of the supporting rollers 33.

In the modification shown in Fig. 3, the face of the supporting roller is provided with irregularities of uniform maximum elevation above the general plane of the face, as with the knurling shown at 58. This knurling decreases further the area of the supporting cylinder which normally contacts the sheet of material being passed over the change of direction roller.

While various dimensions of the various elements may be used, I have found it desirable to have the flat cylindrical face 32 of width, that is, of dimension parallel to the axis of rotation, not substantially more than $\frac{1}{16}$ of the distance at which the supporting rollers 33 are spaced from each other at their nearest points. In a typical assembly in which a sheet three feet in width extends at its edges approximately to the middle of the faces 32, I use to advantage a width of the faces 32 equal to only $\frac{1}{4}$ to 1 inch and ordinarily about $\frac{1}{8}$ to $\frac{1}{4}$ inch, the tapered portion in this instance being about 2 to 4 inches in length measured in direction parallel to the axis of rotation. Between the narrow end of the tapered portion 36 and the outside of the flange 34, the distance is ordinarily a few inches, say 3 to 6. The outer edge of the part 38 of the idling roller may be distant from the axis of rotation $\frac{1}{8}$ inch or so more than the outermost part of the adjacent end of the tapered portion 36 and about $\frac{1}{8}$ to $\frac{1}{4}$ inch less than the face 32 of full width of the roller.

It will be noted that the apparatus includes a series of rollers subdivided into two parts. Guides, in the form of the flanges 34 on each of the spaced parts of the rollers, limit the movement of the strip material laterally in direction away from the other of the two parts constituting in effect a complete roller. It will be noted also that the rollers 20, 22, 24, 26 and 28 are in staggered relationship to each other but are in line. Their axes of rotation are parallel to each other. As a result strip material, drawn by the

driven winder 12 beyond the last of the rollers in the series and applying a pulling force at a right angle to the axes, passes continuously over the several rollers.

The operation of the machine will be largely understood from the description of it that has been given. The strip material to be coated or otherwise processed is passed over the series of change of direction rollers as by being pulled thereover by the power driven winder 12. As the strip material, due to unevenness of the edge, or for other reason, crowds against one of the guides 34, the strip is moved in the direction of the other of the guides, this being made possible by the narrow part 32 of the face of the supporting rollers. With such narrow edge or ribbon face supporting the strip, the strip shifts readily from side to side to accommodate lack of straightness of the edges of the strip.

If for some reason the strip actually varies in width from edge to edge and at a given part of the strip is too narrow to extend completely between the two faces 32, then the strip may rest at one or both edges upon the tapered portion 36. This portion then serves as a supporting part for the narrow strip and remounts the edges upon the faces 32 when the strip in passage over the assembly resumes its normal full width.

In case the strip is temporarily disengaged even from the tapered portions 36, as by the strip becoming extremely narrow in a particular location, then the strip comes to rest at one or both edges upon one or more of the so-called inner rollers 38, 39 and 40. These have a diameter which is somewhat greater than the diameter of the smallest part or end of the tapered portion 36 but somewhat less than the diameter of the ribbon faces 32. As a result, a strip of normal width is supported at its two edges on the ribbon faces 32. It is clear the inner rollers and is free to shift from side to side within the space between the flanges 34. At the same time, the inner rollers are at hand to support the sheet and remount it upon the tapered portions, in case the sheet shows such fluctuations of width as at times to be more narrow than the distance of spacing apart of the inner ends of the tapered portions 36.

The roller assembly of Fig. 2 can be expanded or narrowed so as to make the spacing apart of the centers of the ribbon faces 32 approximately equal to the maximum or normal width of the strip material to be sent over the change of direction rollers.

Various kinds of strip material may be passed over the roller assemblies of kind described as, for instance, strips of steel, aluminum, brass, vulcanized fiber, heavy paper or plastic. The strip material used must be sufficiently flexible to undergo flexing when passed over the rollers without putting objectionably heavy stress upon those rollers. On the other hand, the strip must be sufficiently stiff as not to sag when flexed. Thus, the strip in the position shown in Fig. 2 should extend as a practically straight arch between the faces 32 of the supporting rollers. Also, the strip should be sufficiently strong that the edge of it can support the entire strip in passing over the roller assembly illustrated. While a great variation in the stiffness and calibre of the strip material is permissible, a typical example of a strip that works well is strip steel of thickness 5 to 30 thousandths of an inch.

The chamber 10 may be one which is used to set a coating composition, for heat treating as, for instance, in tempering or chilling an alloy,

or for other uses that are common in the processing of strip material in the form of festoons.

When a coating is applied, as, for instance, in bath 10, the coating may be a usual one which is flowable when applied but sets when subjected to evaporation or to baking. Thus, there may be used oleoresinous coatings, lacquers, heat hardenable but normally flowable plastics, and other conventional coating compositions which require some time for their hardening and therefore are particularly adapted for use on sheets that are to be festooned, so as to extend the time of passage of the sheet through a chamber of given length from the front to the back.

Material of construction of the several parts of my assembly are those that are usual. Thus, the various rollers may be constructed of steel or aluminum. The safety rollers for instance may be constructed also of wood, hard rubber or solid material with a felt cover. Steel is preferred throughout the entire roller assembly.

In addition to the ease of shifting the sheet material from side to side in the assembly of Fig. 2, for instance, and in direction generally parallel to the axis of rotation, the assembly including the supporting rollers with the narrow faces gives a minimum of marring of coating compositions on the surface of the sheet which is passed and flexed over the supporting rollers. Even though the coating when it passes over roller 20, for instance, is still somewhat soft and deformable under pressure, there seems to be a minimum of marring even of the part of the coating that contacts the face 32 of the rollers. In fact, it appears that there may be just sufficient flexing of the sheet so that it contacts the face 32 at a zone which is somewhat more narrow than the whole face 32, as, for instance, along curved line of meeting of the flat and tapered portions of the face of the supporting rollers.

It will be understood that the part of the strip material between the faces 32 normally contacts no part of the assembly and is therefore free from surface marring.

It will be understood also that it is intended to cover all changes and modifications of the example of the invention herein chosen for the purpose of illustration which do not constitute departures from the spirit and scope of the invention.

What I claim is:

1. The change of direction assembly comprising two supporting rollers for strip material to

be passed and flexed continuously thereover, a narrow face on each roller, guide members for restricting lateral movement of the strip, means mounting the rollers rotatably on the same axis and at a distance apart of the faces of the rollers approximately equal to the width of the strip material to be sent thereover so that an edge of the strip material normally rests upon each of the faces, the said guide members being flanges extending from the outer ends of the supporting rollers and each of the said faces having a tapered portion that slopes inwardly on the edge of the face remote from the said flange and serves as a guide and remounting member so as to return the edge of the strip material to the part of the face of the roller of full diameter when the material is temporarily disengaged from the face.

2. The assembly described in claim 1, including an inner roller, of diameter larger than the smaller end of the tapered portion but less than the diameter of the face of the roller at the largest part, and means mounting the inner roller adjacent to the smaller end of the tapered portion and centrally with respect to the axis of rotation of the said rollers and tapered portion, so that the inner roller serves to return, to the tapered portion, strip material temporarily disengaged therefrom.

3. The assembly described in claim 1, the said inner roller being divided into several parts and the assembly including means for shifting the said supporting rollers and parts of the inner roller, along the axis of rotation, so as to vary the spacing of the said parts and the overall width of the assembly.

4. The assembly described in claim 1, the faces of the rollers being provided with knurling in the form of irregularities of surface of uniform maximum elevation above the general plane of the faces, thereby decreasing the area of contact between the said faces and the strip material passed thereover.
